UNITED STATES PATENT OFFICE.

JOHN MARKS, OF BRIGHTON, ENGLAND.

LATCH.

SPECIFICATION forming part of Letters Patent No. 469,863, dated March 1, 1892.

Application filed January 12, 1891. Serial No. 377,455. (Model.)

To all whom it may concern:

Be it known that I, JOHN MARKS, a subject of Victoria, Queen of Great Britain and Ireland, and a resident of Brighton, England, 5 have invented certain new and useful Improvements in Catches or Fasteners for Doors and the Like, of which the following is a specification.

This invention has reference to catches or 10 fasteners for doors, and more especially to fasteners for swing-doors for stores, shops, residences, and the like; and the invention consists of a door provided with a vertical handle, the horizontal arms of which are pivoted to suitable fastening-plates and adapted 15 to engage a transverse slide-piece that produces the withdrawing of a spring-catch or fastener, so that the door can be opened by direct pressure on the handle without specially 20 operating the spring-catch or fastener.

The invention consists, further, in the specific construction of the spring-catch or fastener employed and its connection with the pivoted handle and the plates by which the 25 latter is applied to the door, which constructive details will be fully set forth hereinafter, and finally pointed out in the claims.

In the accompanying drawings, Figure 1 represents a perspective view of my improved 30 handle for swing-doors for stores, shops, residences, &c. Fig. 2 is a horizontal section showing the connection of the handle and its fastening-plates with the door and with the spring-catch or fastener by which the door is 35 held in closed position. Fig. 3 is a perspective view of the spring-catch or fastener shown in Fig. 2. Figs. 4 and 5 are respectively a vertical longitudinal and a horizontal section of an alternative construction of spring-catch 40 or fastener; and Figs. 6 and 7 are perspective views, respectively, of the latch and transverse slide-piece of the fastener shown in Figs. 4 and 5.

Similar letters of reference indicate corresponding parts.

In the drawings, A represents a vertical handle that is used in connection with a swing or other door, said handle being connected by horizontal arms *a* with fastening-plates B, 50 which are screwed to the stile of the door, the plates B being provided with recesses for the pivots *a'* of the horizontal arms *a*. Plates C

are screwed to the plates B for retaining the pivots of the handle A in permanent position on the door, as shown in Fig. 2. The plates 55 *b* at the inner ends of the arms *a* are located inside of the recess formed by the plates B and acted upon by flat springs *b'*, as shown in Fig. 1, which springs are attached to the under side of the plates C and serve to move 60 the handle A away from the door as soon as the pressure on the same is relaxed.

In a mortise of the swing-door D is placed a spring-catch or fastener E, which is inclosed in a socket or housing E', that is retained 65 by a fixed free plate *e* in the mortise of the door, as shown clearly in Fig. 2. In recesses at the rear end of the socket E' is guided a transverse slide-piece F, which is provided at one or both ends with a headed screw- 70 stud *f*, according as a handle A is arranged at one or both sides of the door D. The screw-stud *f* is connected to one of the plates *b* of the handle A, which latter serves thereby to operate the slide-piece F. The shank *e* 75 of a spring-catch E abuts at its rear end against the transverse slide-piece F, while the head of the catch E is provided with guide-pins *e'*, that extend above and below said head and slide in longitudinal slots *e*² in 80 the cylindrical socket E', as shown in Fig. 3. The guide-pins *e'* form pivots, on which the head of the catch may oscillate, so that the rear end or tail of the shank *e* can be moved slightly sidewise. The slide-piece F is provided with a pin *f'*, that is guided in a slot *f*² at the top of the socket E', so as to limit 85 the transverse motion of the slide-piece F. The slide-piece F is preferably made of rectangular cross-section and provided with a recess *e*³ at its lower part, into which the tail of the shank of the catch E is free to enter when the slide-piece is moved in the rear part of the socket E' by pressure on the handle A in connection with the pressure on the head of 90 95 the catch by the pressure exerted on the door. The head of the catch E is thereby pushed back and permitted to disengage the striking-plate of the door-frame, so that the door can be moved into open position. This disengagement cannot take place when the slide-piece F and the handle A are in their normal position, as the tail of the catch E can in this case not enter into the recess *e*³ of the slide-piece 100.

F, but abuts against the solid part of the same until the handle A, being moved toward the door, moves the recess of the slide-piece F into line with the tail of the catch E, so that 5 the tail is free to enter the recess against the tension of its spring acting on the head of the catch, so that the door may be opened.

It has been common heretofore in some instances to provide two inversely-arranged 10 pieces or levers for enabling the spring-latch to be operated from either side of the door, the said levers being beveled or inclined to move or work against correspondingly-beveled recesses formed in the tail or shank of the latch. The device employed in the present invention for enabling the latch to be forced inwardly differs from former inventions, in that it is formed of a single piece or block that is adapted to be operated from one 15 or both sides of the door, accordingly as the handle 5 are arranged on one or both sides thereof, and such construction is much more simple and easy to manipulate. As before stated, the latch itself is arranged to oscillate 20 to a limited extent, so as to insure reliable working thereof, and this latch and slide-piece F, it will be again remarked, are both guided in their movement in the socket so as to operate together or in perfect unison.

30 The fastening described is more especially adapted for single or close-shutting doors, while for double or swing doors the fastener shown in Figs. 4 to 7 may be preferably used. In this fastener the catch E is made with a 35 tapering head and provided with an auxiliary piece or lug E² at its bottom part, which is guided in a corresponding recess in the bottom of the cylindrical tube or socket E', as shown in Fig. 4. The upper part of the socket E' is 40 also slotted for a guide-pin e. The spiral spring for the catch is interposed between the head of the catch E and fixed cheeks at the rear part of the socket, as shown in Figs. 4 and 5. The shank e of the latch E is extended toward the rear end of the socket, its 45 tail being provided with a dovetailed projection e⁴, that engages a corresponding recess e⁵ at the under side of the transverse slide-piece F, which is guided in the rear part 50 of the socket E' in the same manner as before described with the fastener shown in Fig. 3. At the extreme rear end of the socket E' and depending from the top of the same is arranged a fixed block P, that is beveled at 55 its lower end, against which the rear end or tail of the catch E strikes when it is moved back, so that it is depressed by the beveled edge of the block P and its dovetailed projection e⁴ disengaged from the recess e⁵ of the 60 slide-piece F. The catch E is then returned by its spiral spring into its normal position. To the under side of the shank of the catch E and the bottom of the socket E' are applied 65 beveled pins p p', which serve to lift the catch E again, so that its tail end can re-engage the recess in the slide-piece F when it arrives in its normal position. (Shown in Fig. 4.) The

slide-piece F is provided with a headed screw-stud or screw-studs f in the same manner as the slide-piece of the fastener shown in Fig. 3, said stud engaging one of the plates b of the handle A and being operated in the same manner. As soon as the catch E is moved back by the action of the handle on the slide-piece F, which acts on the dovetailed projection on the tail end of the catch, the latter is withdrawn far enough so that the auxiliary lug E² is released from its recess in the striking plate, whereby the beveled end of the catch E is free to leave the striking-plate by the pressure exerted on the door by the handle, the catch being pushed back against the tension of its spring into the socket and its tail end released from the slide-piece F by the beveled block P, upon which the latch is returned to its normal position by its spring, as before described. The slide-piece F is also provided with a pin f', that is likewise guided in a short transverse slot in the top of the socket E', so as to limit the transverse motion of the slide-piece in the same manner as shown in Fig. 3. The slide-piece and its headed stud or studs move in transverse mortises of the door at both sides of the socket, as shown clearly in Fig. 2, the handle and its catch or fastening device forming a convenient and easily-operated means for opening swing-doors, as the withdrawing of the catch or fastener is accomplished by the oscillating motion of the handle, while the closing of the door and the locking of the same are accomplished by the action of the spring-catch in the usual manner.

Having thus described my invention, I claim as new and desire to secure by Letters Patent—

1. The combination of the spring-actuated catch, the slide adapted to engage or release said catch from either direction and consisting of a single block or piece working transversely thereto, the handle for operating said slide, and the movable connection between said handle and slide, substantially as described.

2. The combination of the spring-actuated catch capable of oscillating to a limited extent, the slide adapted to engage or release said catch and permit of the oscillation of the same, a handle for operating the slide, and the movable connection between said handle and slide, substantially as described.

3. The combination of the socket formed with the longitudinal slots at its outer end and provided at its inner end with the recess or opening, the spring-actuated catch having guide-pins working in said slots, the slide for engaging or releasing said catch, provided with a guide-pin working in said recess or opening, a handle for operating the slide, and a movable connection between said handle and slide, substantially as described.

4. The combination, with a swing-door, of a vertical handle having horizontal arms pivoted to fastening-plates of said door, a socket set into a mortise of the door, a spring-actu-

ated catch guided in said socket, and a trans-
verse slide-piece connected to one of the arms
of the handle and guided in transverse re-
cesses of said socket, said slide-piece having
5 a recess for engaging or releasing the tail end
of the latch, substantially as set forth.

5. The combination of a door, a socket set
into a mortise of the door, a spring-actuated
catch or fastener guided in said socket, a
10 transverse slide-piece guided in recesses at
the rear part of the socket, a headed stud at-
tached to the end of the slide-piece, and a ver-
tical spring-cushioned handle having perfo-
rated arms pivoted to fastening-plates of the

door, one of the arms of the handle being con- 15
nected to the headed stud of the slide-piece,
substantially as set forth.

In testimony that I claim the foregoing as
my invention I have signed my name in pres-
ence of two subscribing witnesses.

JOHN MARKS.
